INVENTOR.
Robert E. Power
BY John H. Campbell
ATTORNEY

UNITED STATES PATENT OFFICE.

ROBERT E. POWER, OF LOS ANGELES, CALIFORNIA.

DESIGN FOR A WRITING PENCIL.

Application filed November 23, 1926. Serial No. 19,817. Term of patent 14 years.

To all whom it may concern:

Be it known that I, ROBERT E. POWER, a citizen of the United States, residing at Los Angeles, county of Los Angeles, and State of California, have invented a new, original, and ornamental Design for Writing Pencils, of which the following is a specification, reference being had to the accompanying drawing, forming part thereof.

In the drawing,

Fig. 1 is a front view, and

Fig. 2 is a side view.

I claim:

The ornamental design for a writing pencil, as shown.

ROBERT E. POWER.
